UNITED STATES PATENT OFFICE.

LUCAS EDEL, OF ST. LOUIS, MISSOURI, ASSIGNOR OF ONE-HALF TO THE WESTERN STOVE MANUFACTURING COMPANY, OF SAME PLACE.

COOKING-STOVE.

SPECIFICATION forming part of Letters Patent No. 539,382, dated May 14, 1895.

Application filed May 11, 1893. Renewed February 14, 1895. Serial No. 538,444. (No model.)

To all whom it may concern:

Be it known that I, LUCAS EDEL, of St. Louis, Missouri, have made a new and useful Improvement in Cooking-Stoves, of which the 5 following is a full, clear, and exact description.

The improvement relates partly to the construction of the long center, and its support, and partly to the means for ventilating the 10 oven, substantially as is hereinafter set forth and claimed, aided by the annexed drawings, making part of this specification, in which —

Figure 1 is a vertical central longitudinal section of a cooking-stove having the improvement; Fig. 2, a plan of the stove, its covers being removed; Fig. 3, a vertical transverse section on the line 3 3 of Fig. 2, looking toward the fireplace; Fig. 4, a view similar to that of Fig. 3, omitting the adjoining portions of the stove-top and showing the parts of the long center separated from each other; and Fig. 5, a plan of the parts as exhibited in Fig. 4.

The same letters of reference denote the 25 same parts.

The stove is of the ordinary construction saving as the same is modified or supplemented by the improvement under consideration. Only so much thereof as is needed 30 for an understanding of the improvement is exhibited.

A represents the fire-place; B, the oven; C, the stove-top, and D the flue leading from the fire-place above the oven.

35 E represents the long center. It has been customary to construct this part of a stove in one piece, or if made in separate pieces they have been united to form a part which extends across the opening in the stove top 40 and capable of being handled as a single piece. Such a construction is not wholly satisfactory in that its usefulness is frequently terminated if any portion of the center becomes injured, and if it becomes warped at 45 any point the change in form is liable to so affect the piece throughout its length that it no longer fits properly in its seat in the stove top. I overcome the difficulty referred to by making the center in parts, namely the central part, e, and two end parts e' and e'', which

when joined form a continuous center reaching across the opening, c, in the stove-top, but which are detachable from each other, and more or less free to work endwise on each other. These end parts are preferably 55 similar, and are preferably shaped to be interchangeable. The central part may be, and in the present instance is, made in one piece with the leg, F, which constitutes the central support of the center. The part e is preferably 60 extended laterally to be somewhat wider than the leg, and at its ends, e³, e⁴, it is shaped, substantially as shown, to support the adjoining parts, e' e'', and so that the three parts jointly form a level surface. The center, as a whole, 65 has the usual shape for receiving and supporting the short-centers G, G', and lids H, H' (these parts are indicated in broken lines), in the customary manner. The short centers, so far as the long center is concerned are upheld 70 more especially by the central part e, and the lids by the end-parts e' and e''. 75

The leg, F, so far as furnishing a support for a composite long center such as described is concerned, may be a solid piece, as is customary; but to render the long center a more durable construction, especially when its part e is integral with the leg and, also to provide for ventilating the oven, I make the leg in the form of a flue through which air can be 80 passed and the leg thereby be prevented from becoming as highly heated as it otherwise would be in the use of the stove. The air referred to may be taken from any suitable source, and it may be discharged from the 85 flue in any suitable direction, so long as the air is sufficiently cool, and so long as the operation of the stove is not substantially interfered with. To this end, and also to promote an additional aim of the improvement, 90 namely, the ventilation of the oven, I connect the flue f within the leg F, with the interior of the oven by means of an opening b in the roof b' of the oven, with the air above the stove by means of an inlet e⁵ in the top 95 of the long center, and with the fire place flue D by means of an outlet f'. The air then, when the stove is under way, is drawn through the inlet e⁵ downward into the flue f, and upward into the flue f through the inlet b, and 100

it is discharged into the fire place flue D through the outlet f' , all as is substantially indicated by the arrows in the drawings.

It is unnecessary to provide special inlets 5 for admitting air into the oven, as a sufficient amount usually enters the oven at the joints between the oven doors and the sides of the stove; but if desired additional inlets may be employed.

- 10 I prefer not to be restricted to any special form of leg F so long as it is adapted to carry out the described objects of the improvement. A desirable mode, in practice, of forming the leg and the center-part is shown, the
- 15 leg and center-part being in a single piece, saving a top-piece, f^3 , which is detachable from the remaining portion of the construction, and which can be secured in position so as to complete the construction by means of

the bolt f^4 . The leg is usually bolted to the 20 oven-top substantially as shown at f^5 .

I claim—

In a cooking stove, the combination of the fire place, the flue leading from the fire place, the oven, the long center made in three parts 25 detachably connected together, of the hollow leg made integral with the middle section of said center, communicating with the oven the fire place flue and with the air above the same, forming a support for said center sec- 30 tion and also means for ventilating the oven, substantially as described.

Witness my hand this 3rd day of May, 1893.

LUCAS EDEL.
